UNITED STATES PATENT OFFICE.

JOHN CLARK SPEEDY, OF WAYNESBURG, PENNSYLVANIA.

GARTER.

1,095,746.

Specification of Letters Patent.

Patented May 5, 1914.

Application filed September 22, 1911. Serial No. 650,714.

To all whom it may concern:

Be it known that I, JOHN CLARK SPEEDY, a citizen of the United States of America, residing at Waynesburg, in the county of Greene and State of Pennsylvania, have invented certain new and useful Improvements in Garters, of which the following is a specification, reference being had therein to the accompanying drawing.

This invention relates to garters and more particularly to garters worn by men.

The primary object of my invention is to obviate the necessity of using rubber for retaining a garter in engagement with a limb, and to employ a simple and inexpensive device that will frictionally hold the garter in engagement with the limb without retarding or interfering with the circulation of blood in the limb.

Another object of this invention is to provide a garter with a novel take-up device that permits of the garter being easily and quickly adjusted for limbs of various sizes.

A further object of this invention is to provide a garter consisting of comparatively few parts that are easily assembled and maintained in a sanitary condition.

The above objects are attained by a mechanical construction that will be hereinafter specifically described and then claimed, and reference will now be had to the drawing, wherein:

Figure 1 is a perspective view of the garter, and Fig. 2 is a horizontal sectional view of the same.

A garter in accordance with this invention comprises two straps 1 and 2, preferably made of leather. The rear end of the strap 2 is enlarged and provided with a vertical slot 3 to receive the rear end of the strap 1. The rear end of the strap 1 is bent upon itself and stitched, as at 4 to provide a pocket 5 for a loop 6, said loop having two eyes 7.

Stitched or otherwise secured, as at 8 to the outer side of the strap 2, at a point approximately intermediate the ends thereof, is a short strap folded upon itself to provide a pocket 9 for a wire loop 10 having

eyes 11. These eyes confront and are connected to the eyes 7 by coiled retractile springs 12. The forward end of the strap 2 has a hanger 13 provided with a pocket 14 for a hose fastener 15, this fastener being of the ordinary and well known type of triangular link. The forward end of the strap 2 has a clasp or snap button 16 adapted to be engaged by a plate 17 adjustably supported by the forward reduced end of the end 18 of the strap 1, the reduced end 18 passing through vertical slots 19 provided therefor in the plate 17.

It is through the medium of the coiled retractile springs 12 which serve functionally as a yieldable connection, that the garter is frictionally held upon a limb without retarding the circulation, and said springs are prevented from contacting with the limb by the strap 2.

It is thought that the utility of my improvement will be apparent without further description, and while in the drawing there is illustrated a preferred embodiment of the invention, it is to be understood that the structural elements thereof are susceptible to such changes as fall within the scope of the appended claim.

What I claim is:—

A garter comprising two straps provided with securing means for detachably connecting their forward ends, and having their rear ends overlapped, the rear end of the inner strap having a vertical slot through which the rear end of the other strap extends, a wire loop secured to the rear end of the outer strap, a second wire loop secured to the outer side of the inner strap, said loops being formed with confronting eyes, springs having their ends secured to said eyes, and a hose supporter depending from the inner strap.

In testimony whereof I affix my signature in the presence of two witnesses.

JOHN CLARK SPEEDY.
